(57) **CLAIM**

(21) Appl. No.: **29/158,214**

The design for a unitary lens filter for interactive control systems, as shown and described.

(22) Filed: **Mar. 28, 2002**

DESCRIPTION

(51) **LOC (7) Cl. 14-02**

FIG. 1 is a perspective view of a unitary lens filter for interactive control systems showing our new design with the dashed lines representing the intended environment of the invention;

(52) **U.S. Cl. D14/450**

FIG. 2 is a perspective view thereof;

(58) **Field of Search D14/371-382,**

FIG. 3 is a front view thereof;

D14/125-129, 450; 345/87, 173, 175; 348/818, 819; 359/738, 359; 349/84, 58, 59, 161; 219/210

FIG. 4 is a rear view thereof;

(56) **References Cited**

FIG. 5 is a right side elevational view with the opposite side being a mirror image thereof; and,

U.S. PATENT DOCUMENTS

FIG. 6 is a top plan view with the opposite side being a mirror image thereof.
